FIG. 17 is a front view of the container adapter of FIG. 15, showing how it may be placed upon a container, with the back view being a mirror image thereof;
 FIG. 18 is a cross-sectional view thereof, along an imaginary line depicted using dashes in FIG. 17;
 FIG. 19 is a close-up view of a portion of the cross-sectional view of FIG. 18;
 FIG. 20 is a right-side view of the container adapter of FIG. 15;
 FIG. 21 is a left-side view thereof;
 FIG. 22 is a top view of the container adapter of FIG. 15;
 FIG. 23 is a bottom view thereof;
 FIG. 24 illustrates an exploded view showing individual components of the assembly depicted in FIG. 15;
 FIG. 25 illustrates an as-assembled perspective view of the container with container adapter fitted thereupon from FIG. 15, now illustrating how a syringe may be attached thereto;
 FIG. 26 depicts a side view of FIG. 25;
 FIG. 27 is a cross-sectional view along an imaginary line depicted using dashes in FIG. 26; and,
 FIG. 28 is a close-up view of a portion of the cross-sectional view of FIG. 27.
 Features shown in the drawings using broken lines form no part of the claimed design.
